UNITED STATES PATENT OFFICE

AUGUST E. SCHUTTE, OF NORTHBORO, MASSACHUSETTS, ASSIGNOR, BY MESNE ASSIGNMENTS, TO THE PATENT AND LICENSING CORPORATION, OF BOSTON, MASSACHUSETTS, A CORPORATION OF MASSACHUSETTS

APPARATUS FOR SATURATING FIBROUS MATERIAL

Application filed September 5, 1925. Serial No. 54,612.

This invention in its broadest aspects relates to the saturation or impregnation of fibrous material with waterproofing agents, and more particularly concerns itself with 5 the saturation of the "felt", paper, or equivalent fibrous material commonly employed as the base or foundation for prepared roofing products, with asphalt or other similar bituminous waterproofing agents.

10 Before proceeding to a detailed description of the present invention, however, in order to more fully appreciate the results achieved thereby, it is desirable to discuss certain known facts connected with the production of prepared roofing.

In the saturation of the sheet material or "felt", so called, in the manufacture of roofing, the general practice is to employ as 20 a saturating agent an asphalt of considerably lower melting point than the coating asphalt, which must be of a melting point sufficiently high so as not to be rendered semi-fluid or to "flow" when exposed to extreme solar heat in summer. The sheet of 25 felt is usually saturated by passing it through a bath of saturating or low melting point asphalt.

It is obvious that, the more asphalt the 30 saturated felt contains, the more waterproof and satisfactory it will be for roofing or similar purposes. For increasing the amount of asphalt, past practice has sometimes been directed toward a prolonged 35 saturating action or contact of the felt with asphalt, accomplished, for example, by passing the felt through the asphalt a number of times. Such practice frequently results in a product which has been impaired 40 through scorching, and which is consequently brittle.

If a coating or high melting point asphalt is substituted for the usual saturating or low melting asphalt in saturating the felt, as 45 ordinarily (that is, by passing it through a bath of asphalt), because of the relatively high temperature necessary to fuse or render such coating asphalt molten and sufficiently liquid to ensure saturation, the felt is markedly scorched owing to the length of 50 contact necessary between the asphalt and

the felt in order to effect a satisfactory saturation thereof.

It is, however, highly desirable to employ high melting point asphalt (particularly oxidized or blown asphalt, because of its desirable characteristics) for the saturation of the felt, as well as for the coating thereof, since by such practice the saturating and coating operations may be effected in a single 55 operation. Moreover, the roofing produced thereby is of a more homogeneous or uniform character, since the same asphalt extends throughout the entire cross-section of the sheet and also coats the surfaces thereof, instead of comprising an asphalt coating of 60 different character than the saturating asphalt within the sheet.

Hence the object of the present invention is to provide an efficient method and apparatus for saturation of felt, without impairing the qualities of such felt, either with the usual saturating or low melting point asphalt or with the coating or high melting point asphalt, so-called, so that the felt will 70 contain a maximum amount of saturant.

In accordance with the present invention, provision is made to decrease the time of contact between the saturant and the felt and to increase the rate of the saturating 80 action over past practice. Briefly stated, this is accomplished by forcing asphalt through the sheet, under pressure, during the immersion of the sheet in the bath, thereby effecting a saturation of the felt in a period of time sufficiently short so that the 85 felt remains substantially unscorched and unimpaired in quality. That is, instead of effecting a slow saturation of the felt by allowing it to remain in a bath of molten asphalt until it has been sufficiently penetrated or saturated, this invention provides for a rapid permeation of the felt, so that its constituent fibers and the interstitial spaces and voids therebetween are penetrated in a minimum period of time, by forcing a stream 90 of asphalt under pressure therethrough.

In the practice of the present invention, a continuous sheet of felt is fed continuously into a saturating tank and under what may, for convenience of designation, be termed a 100

slotted "pressure box", submerged in the molten asphalt, and through which molten asphalt is forced against the surface of the sheet throughout its width, under pressure. The asphalt impinges against one face of the felt and passes through the pores or interstices of the felt, displacing the gases and vapor contained therein, which are permitted to escape from the other face, and effects the saturation or impregnation thereof in a minimum period of time, so that either high melting point asphalt or low melting point asphalt may be employed as desired, without scorching the felt.

Moreover, in accordance with the present invention, instead of arranging the usual propelling rolls engaging the saturated web in close proximity to the saturating tank, as ordinarily, so that they not only propel the sheet through the tank but also exert a squeezing action on the saturated felt and remove saturant from the interstices within the felt, as well as superficial asphalt on its surfaces, the propelling rolls may be arranged at a point remote from the tank, and the saturated sheet may be cooled before reaching this point, sufficiently to cause the saturant within the felt to be congealed or hardened so that it is not removed by the propelling rolls. Provision may also be made to scrape or otherwise remove any excess surface asphalt from the sheet after the saturating action and to cool it prior to the scraping action.

The manner in which this invention is practiced, together with other objects and advantages incident thereto, will appear from the following more complete description thereof when taken in conjunction with the accompanying drawings, in which

Figure 1 represents in side elevation an apparatus by which the saturation of the felt may be accomplished.

Figure 2 represents a plan view of the same.

Figure 3 illustrates a section on the line 3—3 of Figure 2.

Figure 4 shows in enlarged detail the pressure box hereinafter described.

Figures 5 and 6 illustrate in larger scale certain detail sections taken respectively on the lines 5—5 and 6—6 of Figure 1.

Figure 7 is a diagrammatic and conventional representation of an apparatus in which the squeeze rolls are remote from the saturating tank.

Referring to Figures 1 and 2 of the drawings 1 and 2 represent a pair of spaced frames, on which a roll of felt or paper 3 may be supported for unwinding. As shown, the roll is carried by a cylindrical core 4, extending therethrough, terminating in a pair of ends 5, 5 of diminishing diameter, which are supported by the forked upper bearing portions 6, 6 of the frames. The roll of paper felt is preferably steadied or ten-

sioned in unwinding, and this may be accomplished by supplying frictional contact on the core. For this purpose, I have provided a pair of brakes, indicated as a whole at B, B, acting on either end of the core. Each brake comprises an arm 7, one end of which is pivotally mounted on a pivot or pin 8, on a bracket 9 which is secured to an end wall of the saturating tank 10. The arm includes an intermediate shoe portion 12 bearing against the core, and is provided with a plurality of notches 13, near its other end, with any selected one of which may engage a hook 14 on which is suspended weights W. The amount of braking or tensioning of the paper may be adjusted or regulated by moving the hooks from one to another of the notches, or by changing the value of the weight W. Any other suitable arrangement for supporting or tensioning the paper in its unwinding may be employed, if desired.

The felt is continuously unwound from the roll 3 and guided into the saturating tank 10 under a slotted cylindrical pressure box indicated at a whole at C, through the slots of which molten asphalt is forced against the felt, and thence proceeds upwardly from the tank between the usual propelling rolls which serve to unwind it and draw it through the tank. The felt accordingly passes from the roll 3 over a guide roll 15, the ends of which are journaled in bearings afforded by a pair of brackets 16, 16 on the sides of the saturating tank 10, and thence proceeds downwardly into the molten asphalt, which is maintained in fluid state by suitable heating means. For this purpose, steam coils 18, supplied with steam through an inlet 19 and from which condensate is removed through an outlet 20, are disposed in sinuous or zigzag courses at the bottom of the tank. The felt is guided under the slotted pressure box C over a guide roll 22, the ends of which are journaled in bearings furnished by a pair of brackets 24, 24 on the sides of the tank.

To maintain the felt in longitudinal alignment immediately under the box (that is, without lateral displacement), as well as to prevent to a practicable extent side leakage or oozing of the asphalt from the space between the box and the felt, the box is provided at its extremities with the cylindrical headers or plates 25 and 26, which also serve as vertical adjusting members for the box, as will hereinafter be described. The molten asphalt is supplied to the pressure box through the header 25 by a supply pipe 30, through a side portion 32 of the tank, of enlarged width.

For the emission of the asphalt, the pressure box is provided on its under side so as to face the felt passed thereunder, with a plurality of slots or openings 29, arranged diagonally side by side and through which the asphalt is emitted under sufficient pressure

to be forced through the sheet passed thereunder and which obstructs the slots and the flow of asphalt therethrough. While I have shown a cylindrical box or pipe having inclined slots therein as a preferred form of pressure box, any other form of box of suitable form may be employed. For example, a rectangular box provided with a longitudinal slot or opening contacting with the entire width of felt sheet may be employed, if desired. The box is preferably maintained stationary in reference to the felt, so that the entire width of the sheet will pass under a flow of asphalt, and as the sheet is fed lengthwise a uniform saturation of the entire sheet will thereby be effected. The asphalt is of course supplied under pressure to the box and is emitted through the slots, impinging against one face of the felt thereunder and forcing its way through the pores and interstices of the sheet to displace the gases and vapors contained therein, which are permitted to escape through the other face, thereby effecting a thorough saturation of the felt in a short time, and hence without scorching it. The brief period of immersion of the felt sheet prior and subsequent to its passage under the pressure box more or less supplements the positive saturating action effected by the asphalt under pressure, and serves to coat the surfaces of the sheet.

As an illustration of certain conditions which must be maintained in practice in order to produce satisfactory saturating action, with an asphalt having a melting point of about 220° F., the molten asphalt is preferably supplied at a temperature between 400° to 425° F. and at the desired pressure as, for example, about 15 pounds per square inch. The pressure and temperature required to give satisfactory results in any specific instance will depend upon the porosity of the sheet. Because of the inclined or diagonal form of the series of slots, as well as the stationary relationship of the box in reference to the moving felt, the entire surface of the felt is subjected to the asphalt under pressure and, as stated, the entire sheet is substantially uniformly penetrated. Moreover, the film of molten asphalt always present between the box and the felt serves as a lubricating film to permit the sheet to travel readily against the asphalt under pressure, and in great measure diminishes the frictional resistance that would ordinarily be encountered in moving felt against a stationary surface. Because of the submerged disposition of the pressure box, splashing of the asphalt is precluded, and the momentum or energy of the asphalt under pressure is cushioned by the bath of asphalt. The buoyant effect exerted on the sheet tends to urge it against the box, thereby assisting in preventing it from being forced or torn away therefrom.

under the force of the asphalt under pressure.

Provision is made to allow the raising and lowering of the pressure pipe from and into the tank for the threading of the felt in initially commencing the saturating action, as well as for the tensioning of the felt, to maintain it against the pressure box. To this end, the headers 25 and 26 are respectively provided with the upstanding lugs 33 and 34, to which are secured respectively the vertically movable threaded shafts 35 and 36. Each shaft may be secured as by screwing its lower end into a suitably threaded aperture formed in the corresponding lug, and then ensuring the fixing of the shaft by a nut 37 on the shaft bearing against the surface of the lug. The vertical movements of the shafts 35 and 36, respectively, may be effected through internally threaded or nut members indicated generally at 38 and 39, the members comprising respectively the bevel gears 40 and 40^a at their upper ends, hub portion 41 and 41^a of diminished diameter journaled in a transverse bar 42 secured to the frame work 43, 43 on the sides of the tank, and collars 44 and 44^a engaging the under side of the transverse member, the shoulders provided by the gears and collars preventing longitudinal play or motion of the nut members. It will be seen that rotation imparted to the nut members causes either an upward or downward motion of the shafts, and that a simultaneous rotation of both shafts must be effected in order to maintain the transverse alignment of the pressure box. Rotation of the shaft 36 may be effected by a bevel gear 46 fixed at one end of a stud shaft 47 and cooperating with the bevel gear 40^a. The gear 46 is journaled in a bifurcated bracket 48 on the frame work, the other portion 46^a of the bracket furnishing a bearing for a transverse shaft 51 which transmits power to the other nut member 38 to effect a vertical movement of the other shaft 35. Rotation of the shaft 51 is effected by a gear 49 at the outer end of the shaft 47, through a gear 51^a cooperating therewith, fixed to one end of the shaft 51. The other end of the shaft 51 is journaled in a bearing afforded by a bifurcated bracket 52 on the framework 43 and is provided with a gear 53 meshing with a gear 54 on one end of a stud shaft 55 which is journaled in the other bearing furnished by the bracket 52. At the inner end of the shaft 55 is a bevel gear 56, meshing with the nut member 38 and imparting rotation thereto in a direction opposite to the rotation of the nut member 39. The shaft 35 is hence threaded in opposite direction to the shaft 36. Rotation of the stud shaft 47 may be effected as by turning a hand wheel 57 fixed at the outer end thereto, rotation of the hand wheel simultaneously raising or lowering both ends of the pressure pipe while

maintaining the transverse alinement thereof. Any other suitable means for threading the paper or raising or lowering the pressure box may be employed.

5 Provision must also be made for allowing the pipe 30, which is connected with the pressure box, to be vertically movable therewith. To this end, I have supplied pipe linkage which maintains asphalt connection to the box in all of its positions while permitting the vertical movement of the box. As shown, the end of the pipe 30 is screwed into one end 58^a of an elbowed swivel joint member 58, in the socket end 58^b of which is swiveled one end of a connecting pipe 59. The other end of the pipe 59 is screwed into one end 60^a of a second elbowed swivel joint member 60, in the female end 60^b of which is swiveled one end of a pipe 61. To take up the angular 10 movement of the connecting pipe 59, the other end of the pipe 61 is swiveled in one end 62^b of a third swivel joint member 62, to the other end of which is screwed a pipe line 63 which communicates with the pump and reservoir (not shown), from which hot molten fluid asphalt is supplied to the pressure box. Any asphalt tending to rise beyond a fixed 15 limit in the tank is removed through an overflow pipe 80 communicating with the tank at one side thereof and may be circulated back to the asphalt reservoir and reemployed for saturating. The pipe 63 may be secured to the side of the tank by a bracket 65, to maintain the pipe connections to the pump and reservoir stationary during the vertical movement of the pressure box. Any other flexible arrangement for allowing the pipe 30 to be raised from or lowered into the tank may be 20 employed.

25 40 After passage under the pressure box, the felt passes forwardly and upwardly over the guide roll 66, journaled in bearings furnished by brackets 67, 67 on the sides of the tank, and thence between the usual propelling and 45 squeeze rolls which serve to propel or draw the felt forward and to squeeze asphalt therefrom. If desired, the rolls 66 and 22 may be made adjustable toward and from each other so as to permit the variation or control of the 50 area of contact between the felt and the box C. The propelling rolls comprise the lower rolls 69 journaled in bearing boxes 70, 70 on guides 76, 76 provided on frame supports 71 fixed to the sides of the tank. The lower roll 55 is driven by a sprocket wheel 96 fixed thereto at an outer end by a chain from a motor or countershaft (not shown). The upper roll is positively driven at a peripheral speed 60 equal to the lower roll by a gear fixed at one end of the lower roll, meshing with a gear 99 fixed to one end of the upper roll.

65 The upper press roll 72 is preferably vertically adjustable in reference to the lower roll. To this end, it is journaled in the bearings 73, 73, vertically movable in the ways

76, 76 and supported at their ends by threaded rods 74, 74 passing through threaded apertures in the ties or struts 75, 75. The lower end of each rod passes through and is journaled in a step bearing afforded by an 70 upstanding boss 73^a in each bearing 73, and is maintained longitudinally fixed in reference thereto by a pin 78 engaging in a groove 79 at the lower end of the rod. To the upper end of each rod 74 is fixed a hand wheel 77, whereupon by turning this hand wheel, the bearing 75 and the end of the rolls 72 supported thereby may be raised or lowered.

75 Instead of locating the squeeze rolls in close proximity to the saturating tank as described, 80 when a supersaturated felt, that is, a felt containing a maximum amount of asphalt, is desired, I may locate these rolls at a point remote from the saturating tank and insert cooling means between the tank and the 85 squeeze rolls, so as to congeal the molten asphalt in the felt prior to passage therebetween. In Figure 7 I have diagrammatically shown such an arrangement, in which the roll of felt or paper 3 is unwound as usual, and is guided over a guide roll 81 downwardly into a tank 82 containing a supply of molten asphalt, and under a guide roll 83, and over a guide roll 85, under the pressure box 86, supplied with asphalt under pressure by a 90 supply pipe 87 from a pump conventionally indicated at 187. The felt passes from the pressure pipe over the guide roll 88, under a guide roll 89, and thence forwardly out of the tank. Any asphalt tending to rise above 95 a certain fixed level overflows through the outlet pipe 90, and is recirculated back to the asphalt supply. It will be seen that as the felt emerges from the saturating tank it has been coated, as well as saturated, by the 100 fluid asphalt. If it were sent through a pair of coating squeeze rolls as usual, the felt would be compressed and a considerable portion of the asphalt between the interstices of the felt would be removed, in addition to the 105 asphalt on its surfaces. In order to have a 110 supersaturated sheet and to maintain the coating thereon, as stated, provision is made to congeal the asphalt sufficiently prior to its 115 passage through the squeeze rolls, so that upon passage therebetween there is no tendency to squeeze and remove asphalt therefrom.

120 While cooling of the sheet may be accomplished by sufficient time of contact with the air of the atmosphere, as shown in Figure 6, cooling of the sheet is effected by causing a cooling medium to play on the surface thereof. Accordingly, as the sheet emerges from the tank, it passes by a nozzle 91 communicating with a blower (not shown), so as to cause air currents to play on the sheet. This may be accomplished by blowing air through the nozzle or by sucking air from the room into the nozzle, the last procedure

being preferable, since in this case the hot vapors and gases emanating from the sheet are removed, thus aiding in the ventilation of the room. The amount of cooling accomplished by the nozzle is preferably controlled so as to maintain the asphalt in a semi-fluid condition. The cooling action tends to condense water vapor contained in the felt and to cool any gases contained therein, thereby forming a partial vacuum therewithin, which causes the asphalt on the surfaces of the sheet to contact as well as to be forced thereto, and to thereby effect a more perfect saturation of the sheet. After the preliminary cooling action, if desired, any superficial or excess asphalt on the surfaces of the sheet may be removed. To this end, a pair of scrapers 92 and 93 may be arranged to act on either side of the sheet in a manner to scrape any excess asphalt from its surfaces without, however, compressing the sheet to cause asphalt to be squeezed from the interior thereof. After the scraping action, provision is made to complete the congealing of the asphalt so that upon passage between the usual propelling or feed rolls there is no tendency for the squeezing or removal of asphalt therefrom. The cooling may be effected by a pair of air nozzles 94 and 95, arranged to act on either or both faces of the sheet and communicating with a fan blower (not shown) which causes air to be forced through or sucked into the nozzles, thereby causing air currents to play on the sheet. The sheet then passes through the coating squeeze rolls 96' and 97', which serve to propel the sheet through the various instrumentalities and to unwind it from the roll. The arrangement in Figure 7 is the preferable one if a super-saturated sheet is to be produced. Where desired, however, the arrangement shown in Figure 1 may be employed and the compression or squeezing after saturation may be controlled by adjusting the upper propelling roll in reference to the lower roll and thereby varying the distance or clearance between the rolls, the pressure on the felt being so regulated as to produce a sheet of the desired saturation.

While I have described an apparatus in which only one pressure pipe has been employed to effect a saturation of the felt, it is of course obvious that a plurality of such pressure units may be employed to effect a more efficient saturation thereof. It is to be observed that the felt also contacts with the bath of molten asphalt maintained in the saturating tank, but the over-all time of contact with the asphalt has been materially diminished, so that there is no tendency for it to become scorched. Where surfaced roofings or shingles are manufactured, the saturated felt may be subsequently coated with asphalt, and further surfaced as by partially embed-

ding mineral grit in the asphalt coating if desired.

One of the advantages incident to the apparatus as herein described lies in the fact that the felt is first preliminarily treated with the asphalt as it enters the bath, causing a partial penetration by the molten asphalt into the sheet, after which in passing under the pressure box the saturation or complete filling of the voids and interstices is completed, and finally as the sheet passes from the pressure box to the surface of the bath, there is ensured the formation of a coating of asphalt on both faces of the sheet. This is all accomplished with a minimum period of saturation and in an apparatus of relatively small size. By limiting the period of immersion, the asphalt may be heated to high temperature without deleteriously affecting the fiber of the felt. Furthermore, variations in the porosity of the felt may be compensated for by varying the pressure upon the asphalt in the pressure box.

Having thus described an embodiment of this invention, it should be evident to those skilled in the art that it is susceptible of various changes and modifications without departing from its spirit or scope as defined in the appended claims.

What I claim is:

1. In an apparatus of the character set forth, a tank for containing a bath of molten asphalt, a stationary cylindrical box submerged in the asphalt in said tank and provided with a plurality of slots arranged diagonally side by side and spaced so that any plane intersecting the cylinder and perpendicular to its axis passes through at least two of said slots, means for supplying asphalt to said box, and rolls for propelling and guiding a sheet of fibrous material through said bath and in contact with said pressure box.

2. In an apparatus of the character set forth, a tank for containing a bath of molten asphalt, a pressure box submerged in the asphalt contained in said tank and provided with openings in a side wall thereof, means for supplying molten asphalt to said box under pressure, means for raising and lowering said box from and into said tank while being supplied with asphalt, a supply pipe for said box, a pair of pipe sections pivotally connected to each other and to said box and said supply pipe, and rolls for propelling and guiding a sheet of fibrous material through said bath and under said pressure box.

3. In a saturating apparatus of the character set forth, a tank for containing a supply of molten asphalt, a pressure box submerged in the asphalt and having a portion perforated for the emission of asphalt under pressure, means for supplying molten asphalt under pressure to said box, rolls located beyond the tank in the direction of feed of the sheet for drawing said sheet through said as-

phalt and in contact with said box, means for scraping excess material from the surfaces of said sheet located between said tank and said propelling means, and means for cooling said sheet located between said scraping means and said rolls.

4. In a saturating apparatus of the character set forth, a tank for containing a supplying of molten asphalt, a pressure box submerged in the asphalt and having a portion perforated to provide emission ports, means for supplying molten asphalt under pressure to said box, means located beyond the tank in the direction of feed of the sheet for drawing said sheet through said asphalt and in contact with said box, means for scraping excess material from the surfaces of said sheet located between said tank and said propelling means, and means for cooling said sheet arranged between said scraping means and said tank and between said scraping means and said propelling means.

5. In a saturating apparatus of the character set forth, a tank for containing a supply of molten asphalt, means for maintaining fluid the asphalt in said tank, a pressure box submerged in the asphalt and having a portion perforated to provide emission ports, means for supplying molten asphalt under pressure to said box, means for raising and lowering said box from and into said asphalt, rolls for drawing said sheet through said asphalt and in contact with said pressure box, scrapers positioned to engage the surfaces of said sheet to remove excess asphalt therefrom located between said tank and said propelling rolls, and nozzles arranged to pass a cooling medium over the surfaces of said sheet between said scrapers and said tank and between said scrapers and said propelling rolls.

6. Apparatus of the class described, comprising means for maintaining a bath of liquefied asphaltic material, means for drawing a sheet of indeterminate length through said bath, means for subjecting one face of a portion of the submerged sheet to asphalt at a pressure greater than that of the asphalt on the opposite face of the sheet, and means located between said bath and said drawing means for successively partially cooling the sheet, scraping excess asphalt from the sheet, and further cooling the sheet.

In testimony whereof I have affixed my signature.

AUGUST E. SCHUTTE.
